UNITED STATES PATENT OFFICE.

JOSEPH NOVAK AND JOSEPH STROBEL, OF CHICAGO, ILLINOIS.

FOLDING BED.

SPECIFICATION forming part of Letters Patent No. 254,363, dated February 28, 1882.

Application filed December 2, 1881. (No model.)

To all whom it may concern:

Be it known that we, JOSEPH NOVAK and JOSEPH STROBEL, both of Chicago, in the county of Cook and State of Illinois, have invented certain useful Improvements in Folding Beds, of which the following is a full, clear, and exact description.

Reference is to be had to the accompanying drawings, forming part of this specification, in which similar letters of reference indicate corresponding parts in all the figures.

Figure 1 is a plan view of our improvement extended for use, part of the wire mattress being broken away. Fig. 2 is a sectional side elevation of the same, taken through the line *x* *x*, Fig. 1. Fig. 3 is the same section as Fig. 2, but showing the bed folded.

The object of this invention is to apply woven-wire mattresses to folding beds.

The invention consists in a novel construction and arrangement of parts, as hereinafter described, and pointed out in the claims.

A represents a folding bedstead, which folds together at the center. The folding hinges *B* are attached to the adjacent ends of strips *C*, hinged to the upper edges of the side boards of the bedstead *A*, which are recessed to receive the said strips, as shown in Figs. 1 and 2. When the bedstead *A* is opened for use the hinged strips *C* are turned down against the outer sides of the said side boards to lock the bedstead open and at the same time make it more convenient for a person getting into and out of bed.

D are latches, which are hinged to the bottom of one part of the bedstead in such positions that they will engage with catches *E*, attached to the bottom of the other part of the bedstead. The latches *D* are held in gear with the catches *E* by the wire springs *F*, attached to them and to the hinging-rod *G*, with which the said latches *D* are rigidly connected.

Upon the ends of the rod *G* are formed, or to them are rigidly attached, arms *H*, which project in the opposite direction from the latches *D*, so that the said latches *D* can be raised from the catches *E* by operating the said arms *H*. The arms *H* are operated by cords *I*, attached to them, and which pass out through holes in the bottom of the bedstead, as shown in Figs. 2 and 3.

The bedstead is supported upon legs *J*, which have casters *K* attached to their lower ends, and are hinged at their upper ends to supports *L*, attached to the bottom of the bedstead. 55

To the lower parts of the legs *J* are hinged the lower ends of brace-rods *M*, the upper ends of which are hinged to the bottom of the bedstead near its joint. With this construction the rods *M* brace the legs *J* in position when 60 the bedstead is opened, as shown in Fig. 2, and draw and hold the said legs against the bottoms of the parts of the bedstead when the said bedstead is folded, as shown in Fig. 3.

N is a woven-wire mattress, the ends of 65 which are attached to the bar *O* and the roller *P*, respectively.

To the ends of the bar *O* are attached short levers *Q*, the lower arms of which are pivoted to supports *R*, attached to the lower parts of 70 the head ends of the side boards of the bedstead *A*. To the upper arms of the levers *Q* are hinged the ends of rods *S*, which extend along the inner surfaces of the head parts of the side boards of the bedstead *A*, and pass 75 through guides *T*, attached to the said parts. The ends of the rods *S* project across the joint in the side boards of the bedstead, so as to strike against the concaved surface of the stop-blocks *U*, attached to the foot parts of the bed- 80 stead side boards. With this construction when the bedstead is opened the ends of the rods *S* strike the stop-blocks *U* before the said bedstead is fully opened so that the opening of the bedstead will press the rods *S* toward 85 the head of the bedstead, moving the bar *O* in the same direction and putting the mattress *N* under tension. With this construction when the bedstead begins to move in being closed the mattress *N* is slackened and readily folds 90 between the parts of the bedstead, as shown in dotted lines in Fig. 3.

V are spiral springs placed upon the rods *S*. One end of the springs *V* rests against the guides *T*, and their other ends are attached to the rods 95 *S*. The springs *V* are designed to support part of the rearward pressure of the rods *S*, and prevent the said rods from pressing so hard against the stop-blocks *U* as to force the bedstead side boards apart at the lower ends of 100 their joints. The ends of the foot-roller *P* work in sockets *W*, attached to the foot ends

of the side boards of the bedstead. To the ends of the roller P are attached levers X, which move along catch-bars Y, attached to the side boards of the bedstead, so that the tension of the mattress can be regulated by adjusting the levers X. This construction also allows a greater tension to be given to one side of the mattress than to the other, if desired—as, for instance, when one of two persons who are to sleep in the bed be heavier than the other.

The middle part of the mattress N is supported by spiral springs Z, attached to the bottom of the bedstead, as shown in Figs. 1 and 2.

Having thus fully described our invention, we claim as new and desire to secure by Letters Patent—

1. In a folding bed, the combination, with the side boards of the bedstead and the bar O, to which one end of the mattress is attached, of the pivoted levers Q attached to the ends of the said bar, the rods S, and the concaved stop-

block U, substantially as and for the purpose set forth.

2. In a folding bed, the combination, with the side boards of the bedstead, the bar O, and the mattress N, of the pivoted levers Q, the rods S, stops U, and springs V, substantially as and for the purpose set forth.

3. In a folding bed, the combination, with the latches D and the catches E, of the rod G, provided with the arms H, the springs F, and the cords I, attached to said arms and passing through the bottom of the bed, substantially as and for the purpose set forth.
